UNITED STATES PATENT OFFICE

2,186,952

ELASTIC FLUID TURBINE

David J. Bloomberg, Newton, Mass., assignor to
 General Electric Company, a corporation of
 New York

Application June 21, 1938, Serial No. 214,909

3 Claims. (Cl. 253—78)

The present invention relates to elastic fluid turbines in which elastic fluid discharged from the bucket wheel of a higher stage is conducted to the diaphragm of a lower stage considerably spaced from the bucket wheel of the higher stage. Axial spacing of turbine stages is necessary, for instance, in cases in which the first stage includes a large diameter Curtis type bucket wheel from which the fluid is to be conducted to a second stage small diameter diaphragm. It has been found that considerable energy loss of the elastic fluid takes place on its path between axially considerably spaced stages, particularly when the higher stage is operated with partial admission, that is, when the elastic fluid is supplied only along a comparatively small arc of the higher stage.

The object of my invention is to provide an improved construction and arrangement of elastic fluid turbines whereby the aforementioned drawback is overcome. This is accomplished in accordance with my invention by the provision of an elastic fluid guiding and directing device intermediate axially spaced stages of a turbine.

For a consideration of what I believe to be novel and my invention attention is directed to the following description and the claims appended thereto in connection with the accompanying drawing.

In the drawing Fig. 1 illustrates a sectional view of an elastic fluid turbine embodying my invention; Fig. 2 shows a section along lines 2—2 of Fig. 1; and Fig. 3 shows a modification of my invention.

The arrangement of Figs. 1 and 2 comprises a turbine casing 10 with inlet conduits 11 connected to a chest 12. The chest has a plurality of partitions 13 dividing it into several, in the present instance 6 sections. A rotor is disposed within the casing and includes a shaft 14, a first stage large diameter bucket wheel 15 and a second stage small diameter bucket wheel 16 secured to the shaft 14. Elastic fluid is conducted from the chest 12 to the nozzle forming buckets of the first stage wheel 15 by means of a first stage diaphragm or nozzle plate 17 suitably secured to and supported on the casing 10. Elastic fluid discharged from the nozzles of the first stage bucket wheel 15 is conducted to the second stage bucket wheel 16 by means of a second stage nozzle diaphragm 18 provided ahead of the second stage bucket wheel 16 with regard to the direction of flow of fluid. The nozzle diaphragm 18 has an outer ring 19 secured to the casing 10 to support the diaphragm 18.

The arrangement so far described is typical of elastic fluid turbines with partial admission of elastic fluid to the first stage bucket wheel. During starting, elastic fluid is supplied through one of the inlet conduits 11 to a section of the first stage diaphragm 17, whence this fluid is directed to a section of the first stage bucket wheel 15 adjacent the aforementioned section of the first stage diaphragm 17. Thereafter valve means, not shown, provided in the other conduits 11 are successively opened, thus increasing the arc of admission of elastic fluid to the first stage. With all inlet valves in opening position fluid is supplied to the first stage over an angle of about 120° and fluid is discharged from the first stage wheel 15 over a similar angle of about 120°. In order to reduce energy loss in the space between the wheel 15 and the second stage diaphragm 18, due to whirling and rotation of the fluid in said space, I provide means for properly directing and guiding the fluid on its path from the first stage to the second stage. In a preferred embodiment this means acts at the same time to effect distribution of the elastic fluid in the second stage and thereby increases the efficiency of the latter. The guiding and directing device comprises a plurality of vanes 20 intermediate the first and the second stage. These vanes in the present instance are secured to a curved plate or ring segment 21 which in turn is fastened to the outer ring 19 of the diaphragm 18 by means of a plurality of screws 22. The vanes are arranged along an arc having a center coinciding with the center of the shaft. The length of the arc is about 120°, that is, equal to the total arc of admission. The vanes have outer, straight or plane portions 23 which are inclined about 45° from the corresponding direction through the center of the shaft. With the exception of the two vanes shown on the right-hand side of Fig. 2 the vanes have curved portions 24, the curved portions of the vanes shown on the left-hand side being longer than the length of the curved portions shown on the right-hand side of Fig. 2 in order to effect substantially uniform distribution of the elastic fluid discharged from the first stage among the sections of the second stage. The direction of flow of fluid is indicated by arrows in the drawing. During operation, fluid discharged from the first stage wheel 15 is directed axially and radially inward by the vanes 20 towards the nozzles of the diaphragm 18. The vanes 20 also reduce rotation in the space between the first and the second stages.

The arrangement of Fig. 3 comprises a casing 25

25 forming an inlet chest 26 with an admission opening 27. A first stage including a diaphragm or nozzle blade 28 and a Curtis type bucket wheel 29 and a second stage including a diaphragm 30 5 and a bucket wheel 31 are formed within the casing 25. The second stage has a smaller diameter than the first stage and is axially considerably spaced from the latter. The elastic fluid directing device disposed between the two stages 10 comprises a plurality of straight or plane vanes 32 with outer edges fused to a ring 33, which latter is fastened by bolts 34 to an outer portion of the first stage diaphragm 28. An inclined ring segment 35 is welded to the blades 32 and to the 15 supporting ring or member 33 for properly directing the elastic fluid discharged from the first stage towards the inlet openings of the nozzles of the second stage diaphragm as indicated by arrows. 20

20 The elastic fluid guiding and directing device for conducting elastic fluid from a high stage bucket wheel to an axially spaced low stage diaphragm may be used advantageously in any arrangement in which elastic fluid is admitted to 25 the full arc or a partial arc of either stages and in which the diameter of one stage differs substantially from that of the other stage.

Having described the method of operation of my invention, together with the apparatus which 30 I now consider to represent the best embodiment thereof, I desire to have it understood that the apparatus shown is only illustrative and that the invention may be carried out by other means.

What I claim as new and desire to secure by 35 Letters Patent of the United States is:

1. An elastic fluid turbine comprising a first stage having a bucket wheel of large diameter and a second stage with a diaphragm of small diameter considerably axially spaced from said 40 bucket wheel, and a device comprising a plurality

of spaced vanes arranged on an arc with each vane having a straight portion inclined by about 45° towards the corresponding diameter of the bucket wheel and some of the vanes having curved portions to direct elastic fluid discharged from the bucket wheel and effect distribution of the fluid among all sections of the diaphragm. 5

2. An elastic fluid turbine comprising a high pressure stage with a bucket wheel, partial admission means for conducting elastic fluid to an arc 10 of the bucket wheel, a low pressure stage with a diaphragm for receiving elastic fluid discharged from the bucket wheel, the diaphragm being considerably axially spaced from the bucket wheel and having a diameter substantially different 15 from that of the bucket wheel, and a guiding and directing device interposed between the bucket wheel and the diaphragm and extending over an arc substantially equal to the arc of admission to the bucket wheel for guiding elastic fluid from the bucket wheel exit arc to the diaphragm, said device having a plurality of vanes with outer straight portions inclined by about 45° towards the corresponding bucket wheel diameters. 20

3. An elastic fluid turbine comprising a first stage having a bucket wheel, a second stage with a diaphragm considerably axially spaced from the bucket wheel and of a diameter substantially different from that of the bucket wheel, and a 25 device comprising a plurality of spaced vanes arranged on an arc with each vane having a straight portion inclined by about 45° towards the corresponding diameter of the bucket wheel and some of the vanes having curved portions to direct elastic fluid discharged from the bucket wheel and effect distribution of the fluid among all sections of the diaphragm. 30
